UNITED STATES PATENT OFFICE.

OSCAR E. LARSON, OF PEORIA, ILLINOIS.

SPRING-MOTOR.

1,118,207.

Specification of Letters Patent. Patented Nov. 24, 1914.

Application filed November 21, 1912. Serial No. 862,833.

To all whom it may concern:

Be it known that I, OSCAR E. LARSON, a citizen of the United States, residing at Peoria, in the county of Peoria and the State of Illinois, have invented certain new and useful Improvements in Spring-Motors, of which the following is a specification.

The object of my invention is to construct an improved spring-motor which shall derive its resulting power from a series of co-operating spiral band-springs to enable a maximum uniform power to be resultant; and further, to provide an improved means for mounting the band-springs and for transmitting their actions one to another.

In the accompanying drawings:

Figure 1 is a view in section through an embodiment of my improved spring-motor, as taken on the line 1—1 of Fig. 2. Fig. 2 is an end view of the spring-motor, looking at the winding end of Fig. 1. Fig. 3 is a sectional view through the first wound spring as taken on the line 3—3 of Fig. 1. Fig. 4 is a transverse sectional view on the line 4—4 of Fig. 1, showing the second wound spring. Fig. 5 is a transverse sectional view as taken on the line 5—5 of Fig. 1. Fig. 6 is a view in elevation of the spring motor.

The spring-motor in itself is mounted entirely upon a shaft 7 and this shaft can be suitably supported in relation to means to be driven by the motor; it being understood that a motor of this type can be mounted in various devices and machines for supplying a stored up spring energy; and in the present case the shaft 7 is journaled at its ends in bearing brackets 8, the winding means are in the form of a crank 9 journaled in a bracket 10 and carrying a spur-gear 11 in mesh with a spur-gear 12 journaled loosely upon and adjacent one end of shaft 7, and the means to be driven by the motor is a shaft 13 having a fixed spur-gear 14 meshing with a spur-gear 15 mounted loosely on the end of shaft 7 opposite gear 12.

A sleeve 15' is mounted keyed to shaft 7 with one end abutting the hub of gear 12; and mounted loosely rotatable upon said

sleeve and spaced from gear 15 is a spoked casing 16 held fixed to gear 12 by bolts 17 which hold the casing 16 upon a peripheral casing 18 interposed between members 12 and 16. A band-spring 19 is located within the inclosure thus formed, is coiled spirally from its inner end counter-clockwise as seen in Fig. 2 about the sleeve 15', with its said inner end fixed at 20 to said sleeve and its outer end fixed at 21 to a bolt 17. A sleeve 22 is keyed to shaft 7; and mounted loosely upon sleeve 22 is a side casing 23, which together with side casing 24 mounted loosely upon shaft 7, and peripheral casing 25, form an inclosure for a second spring, the casings 23 and 24 being bolted upon casing 25 by bolts 26. A band-spring 27 is located within this casing, is coiled spirally about sleeve 22 in a direction opposite to that of spring 19, and has its inner end fastened to sleeve 22 and its outer end fastened to one of the bolts 26. A sleeve 28 is mounted loosely upon shaft 7, is connected fixedly to the side casing 24 by a collar 29, and a spring casing 30 similar to the aforementioned casings is mounted loosely upon sleeve 28 and shaft 7, inclosed a band-spring 31 with its inner end attached to sleeve 28 and its outer end to casing 30, one side of casing 30 being formed by the gear 15 which transmits the spring force from the motor. A pawl 32 pivotally mounted on shaft 7 engages gear 11 and holds same from backward movement, that is, from movement against that for winding up the springs. Thus there are three band-springs co-operatively connected to transmit motion one to another; but the connection between the sleeves of two adjoining springs might be differently constructed, for instance, the sleeves 15' and 22 need not be keyed to shaft 7 but be one integral sleeve loose upon the shaft, the present construction being shown to illustrate the fact that the first two springs may be mounted on the shaft at points spaced any distance apart for the purpose of avoiding intermediate obstructions; and similarly sleeve 28 could be integral with casing 25, this construction shown being very useful as a feature in assembling the spring-motor. To utilize a

greater number of springs the added springs would bear the same relation and connections as spring 31 is to spring 27.

Assuming shaft 13 to be locked against rotation, the crank 9 is turned in the direction shown in Fig. 2 to wind up the springs. Thus the spring 19, the first, is wound from its outer end; and since the resistance to the inner end 20 of spring 19 is that of the inner end of spring 27, said inner end 20 will turn said inner end of spring 27 winding up the latter spring from its inner end in a manner opposite to the winding of spring 19. The resistance to the outer end of spring 27 being that of the inner end of spring 31, said spring 31 will be wound up from its inner end in a manner similar to spring 27. The outer end of spring 31 being fixed, the spring limit is reached. In this winding the winding of the springs is to an extent simultaneous, that is, the winding is divided proportionally to the several springs according to their resistance, the first spring being wound until its wound end causes a resistance great enough to transmit winding movement to the second, and in a like manner the end of the second to the winding end of the third; and this proportion will continue, the first spring being wound first, then the second and third, respectively. The resulting spring force is in the same direction as the winding force expended. The spring energy of the motor is now ready to be expended and transmitted to means to be operated; and by rendering shaft 13 free to rotate it will be turned by the spring force at a rate according to its working resistance. In this unwinding of the spring it will be observed that the casing of the spring 19 is held from rotation (unwinding action) by the pawl 32, and that the fixed resistance ends of springs 27 and 31 rotate as their spring force is being expended; therefore, the energy of the three springs combine to develop the resulting power in a manner so that they individually expend their forces at different rates, each reaching their limit at different times; thus a spring force is resultant that is substantially uniform throughout a greater part of its expending of energy.

I claim as my invention:

1. A spring-motor, having a series of concentrically mounted spiral band-springs, connections between the springs including, a connection between the inner ends of two adjoining springs, and a connection between the outer end of one of said two springs and the inner end of a third spring.
2. A spring motor, comprising a plurality of springs connected in series, the first of the series being an initial winding spring and the last being a resultant power spring, the winding spring and resultant spring

being wound in opposite directions, means 65 for winding the first spring of the series in one direction, and means connected with the last spring of the series to be driven thereby in a direction opposite to that of the winding means.

3. In a spring-motor, the combination of a spiral band-spring adapted to be wound from its outer end, a spiral band-spring having its inner end connected to the inner end of the first mentioned spring, and a 75 spiral band-spring having its inner end connected to the outer end of said second mentioned spring and adapted to transmit the spring force of said springs through its outer end.

4. A spring motor, comprising a plurality of springs connected in series, means for winding the springs from the outer end of the first spring of the series, and means connected to the outer end of the last spring 85 of the series, to be driven thereby.

5. In a spring-motor, the combination with a shaft, of a sleeve mounted on the shaft, a spiral band-spring wound about the sleeve and having its inner end connected thereto, a member loosely mounted on the shaft and attached to the outer end of the said spring, a spiral band-spring wound about the shaft in a direction opposite to the first mentioned spring, having its inner 95 end connected to said sleeve, and a member loosely mounted on the shaft and connected to the outer end of the second mentioned spring, said first mentioned member adapted to be rotated to wind the 100 springs.

6. In a spring motor, a pair of oppositely wound springs the inner ends of which are connected in such a manner that one of the springs is wound through winding of the other, and a third spring having its inner end connected with the outer end of said spring that is wound, said third spring being wound in a like direction therewith.

7. In a spring motor, two springs the inner ends of which are so operatively connected that the two are not wound simultaneously, and a third spring the inner end of which is so operatively connected with the outer end of one of the first two springs 115 that none of the springs are wound simultaneously.

8. In a spring motor, two oppositely wound springs, means connected with the outer end of one of the springs for winding 120 the same, an operative connection between the inner end of said driving spring and the inner end of the other spring, and driven means connected with the outer end of the driven spring.

9. In a spring motor, the combination of a shaft, a spring coiled thereabout with one end fixedly connected thereto, means for

winding the other end of the spring, and a series of springs wound about the shaft in a direction opposite to that of the first named spring, one of the springs connected to the shaft, and the springs of the series being so connected that they will be wound by winding of the shaft-connected spring.

In testimony whereof I have hereunto set my hand in presence of two subscribing witnesses.

OSCAR E. LARSON.
